UNITED STATES PATENT OFFICE

ALBERT B. COLLINGBOURNE, OF ELGIN, ILLINOIS

DESIGN FOR A COMBINATION BOX BLANK AND CUTOUT CARD

Application filed March 12, 1932. Serial No. 43,171. Term of patent 7 years.

To all whom it may concern:

Be it known that I, ALBERT B. COLLINGBOURNE, a citizen of the United States, residing at Elgin, in the county of Kane and State of Illinois, have invented a new, original, and ornamental Design for Combination Box Blank and Cutout Card, of which the following is a specification, reference being had to the accompanying drawing, forming part thereof.

The figure of the drawing is a plan view of the combination box blank and cutout card showing my new invention.

I claim:

The ornamental design for a combination box blank and cutout card, as shown.

ALBERT B. COLLINGBOURNE.
